UNITED STATES PATENT OFFICE.

WALTER MOLL, OF EVANSVILLE, INDIANA, ASSIGNOR TO FRED W. GOEDEKE, OF EVANSVILLE, INDIANA.

STOVE AND OVEN DOOR.

Application filed August 3, 1926. Serial No. 126,900.

This invention relates to an improved oven door of the type which consists of two pressed steel plates or panels secured together, with hinge members secured within the corners thereof, and formed with projecting hinge elements.

The general object of the invention is to provide, in a device of this type, a simple and practical construction, wherein the several parts of the door are securely held together without any screws, bolts or other fastening devices being visible from outside the door, except those which secure the handle, so that the face of the door may be made in any desired design, and will present a smooth and attractive appearance. In the present embodiment of the invention, the hinge members are bolted or otherwise effectively secured to the inside plate or lining of the door, and the front plate or panel is provided with a rearward flange having an inturned lip, forming a channel in which the hinge members and adjacent edge of the lining are tightly held.

The detailed construction of the invention will be more particularly explained in connection with the accompanying drawings, which illustrate the same in its preferred form.

30 In the drawings:

Figure 1 is a front elevation of the door as used on a gas range.

Figure 2 is a rear view of the door, partly in elevation and partly in section.

35 Figure 3 is a section taken on the line 3—3 of Figure 2.

Figure 4 is a section taken on the line 4—4 of Figure 2.

40 Figure 5 is a sectional view of the outer and inner plates of the door, with the other parts omitted.

Figure 6 is an isometric display view showing the parts ready to be assembled.

45 Figure 7 is an isometric view of a portion of a door with a modified form of hinge.

The invention, as herein described, is adapted to be used on a gas range 10, and comprises an outer steel plate 11, which may be pressed to present any desired design, and an inner plate or lining 12. Within the lower corners of the door, hinge members 13 are secured to the inner face of the lining 12 by screws 14 or the like. The blocks 13 are formed with arcuate hinge

55 elements 15 adapted to project through

openings 12 formed in the lining 12 and on which the door is adapted to swing in a well known manner, one of said arcuate members 15 being provided with an aperture 15^a, at its terminal, for connection with a suitable coiled spring (not shown) to cause the automatic closing of the door, while the other member 15 is provided with a lug 15^b to form a stop for the door and hold the same in a horizontal position when open. 60 The outer plate 11 is formed on three sides with a flange 16, within which fits a flange 17 formed on the corresponding three sides of the lining 12. The fourth or lower side of the plate 11 is formed with a flange 18, 65 having an inturned lip 19, which fits tightly over the offset lower portion 20 of the lining 12. The ends of the flange 18 are spaced from the ends of the flange 16, where the latter curve around the lower corners, to form 70 openings 21, through which project lugs 22 formed integrally with the hinge members 13 and serving, in addition to the aforesaid screws 14, to form a more rigid seat for the hinge member between the front and back 75 plates of the door. Between the hinge members 13, the lining 12 is provided with a flange 23, which fits tightly in the bottom of the channel formed between the lip 19 and the main portion of the front plate 11, and also bears against the flange 18 of the plate 11, as clearly shown in Figure 2 of the drawings.

When the door is assembled, the hinge blocks 13 are placed within the peripheral 90 flanges of the front plate 12 with the lugs 22 projecting through the opening 21. The lining 12 is then placed in position with its lower offset portion 20 beneath the lip 19, and the hinge members are secured to the 95 lining by the screws 14. The lining and the hinge members form a tight fit beneath the lip 19, and the hinge members are provided with angularly disposed arms 13^a which extend diagonally across the upper end portions of the door to points adjacent to the top flanges 16 and 17, and are there provided with apertures to align with holes 24 formed in the upper portion of the lining 12 for receiving bolts 25, which secure the handle 26 100 to the front plate 11, and the latter to the lining 12. The nuts of the bolts 25 are held from turning by depressed seats 24^a in the lining 12. Thus, the parts of the door are securely held in assembled relation without 105 110

any bolts or other fastening devices showing on the front face of the door, and the hinge members are materially strengthened, and their connection with the door rendered 5 more rigid, by reason of their elongated arms 13^a extending diagonally across the end portions of the door and having connection with the handle fasteners 25.

In the form shown in Figure 7, the hinge 10 block 27 is formed with an outwardly projecting hinge trunnion 28, which is formed integrally with the block and extends outwardly at the lower corner of the door, in substantially horizontal alinement with the 15 lower edge of the latter, there being one at each side. In this construction, the flanges 16 and 19 are provided with openings 29 and the lining 12 is, of course, cut away, as shown at 30, to provide an opening 20 through which the trunnion 28 projects, and the flanges 16 and 20 are likewise suitably formed for the purpose.

It is, of course, to be understood that the invention may be adapted to doors of various 25 designs other than those illustrated, either on gas or coal ranges. It is also to be understood that various modifications may be made in the construction of various parts of the door without any material departure 30 from the salient features of the invention as claimed.

What is claimed is:—

1. In an oven door, the combination of an outer plate and an inner plate spaced apart 35 and having interfitting peripheral flanges, hinge blocks in the space enclosed between the two plates and secured at their lower ends to the inner plate only, means formed on the lower part of the outer plate and invisible from outside the door for receiving 40 and retaining the lower edges of the hinge blocks and inner plate, a handle on the upper part of the door, and unitary means for securing the handle and adjacent portions 45 of the hinge blocks and inner plate to the outer plate.

2. In an oven door, the combination of an outer plate and an inner plate spaced apart and having interfitting peripheral flanges, 50 hinge blocks in the space enclosed between the two plates and secured at their lower portions to the inner plate only, the flange on one edge of the outer plate having an in-turned lip forming a channel in which the 55 adjacent edge portions of the hinge blocks and inner plate are held, and means for securing the opposite edge portions of the inner plate and the hinge blocks to the outer plate.

60 3. In an oven door, the combination of an outer plate and an inner plate spaced apart and having interfitting peripheral flanges, hinge blocks in the space enclosed between the two plates and having inclined 65 arms extending upwardly and inwardly to-

wards said flanges, said blocks being secured to the inner plate only at their lower ends, the flange on one edge of the outer plate having an in-turned lip forming a channel in which the adjacent edge portions of the hinge blocks and inner plate are held, said inner plate having an inwardly offset portion extending underneath said lip and formed with a flange bearing against the inner face of the outer plate, said hinge 75 blocks being formed to fit beneath said inwardly offset portion, and means for securing the opposite end portions of the arms and the inner plate to the outer plate.

4. In an oven door, the combination of an outer plate and an inner plate with a space therebetween, hinge blocks disposed in said space and secured at their lower ends to the inner plate only, means formed on one edge portion of the outer plate and invisible from outside the door for receiving and retaining the corresponding edge of the inner plate and the adjacent edge portions of the hinge blocks, and means for securing the opposite edge portion of the inner plate and the upper ends of the blocks to the outer plate.

5. In an oven door, the combination of a front plate and a back plate having interfitting marginal flanges to provide a space therebetween, hinge blocks located in said space at the bottom of the door and adjacent to each end of the same, said blocks being secured to said back plate, the lower flange of the front plate having an in-turned lip to bear upon the outer face of the lower edge portion of the back plate to hold the parts together without exposing bolts on the front of the door, said hinge blocks having arms extending to the top of the door and inclined towards the center thereof to be traversed and held by the handle bolts of the door, and said interfitting flanges having coacting openings at the lower corners of the door to allow the hinge elements of the blocks to project therethrough.

6. In an oven door, an inner plate having flanges extending at right angles to the plane of the plate on its top, bottom and side edges, an outer plate having flanges extending at right angles to the plane of the plate on its top and side edges to receive the top and side flanges of the inner plate and having at its bottom a U-shaped channel portion to receive and fit over the bottom flange of said inner plate, hinge blocks in the space between said plates, said inner plate and said outer plate having openings in their flanges, and said hinge blocks having elements projecting through said openings, means securing said hinge blocks to adjacent the bottom of said inner plate to be carried thereby and free of said outer plate, and means adjacent the top of said plates for securing said plates removably together, all being arranged whereby upon release of said plate-securing means

said outer plate may be removed without disturbing said inner plate and hinge blocks.

7. In an oven door, an outer plate having its edges extended over at right angles to 5 constitute flanges at four sides and having the bottom flange interrupted at the sides to constitute openings and having that portion between the openings provided with a lip extending back parallel to the body of the plate, 10 thereby constituting a substantially U-shaped channel portion, an inner plate having its top, side and bottom edges extended at right angles to constitute flanges to fit within the flanges and channel of said outer plate, said 15 inner plate being inwardly offset along its lower edge to receive the lip of said U-shaped channel member whereby said lip will lie flush with the outer face of said inner plate, and hinge elements located between said 20 plates and having portions projected through openings in said flanges, and means securing said plates together at the top whereby said outer plate may be removed from said inner plate substantially as specified.
- 25 8. In an oven door, an outer plate having right angled flanges on all four sides, the flange along one side having an inturned lip thereby constituting a channel along that side, an inner plate also having a right angled flange on all four sides to fit within the flanges and channel of said outer plate, hinge 30 elements located within the space between

said plates, means located adjacent the edge of said plates opposite the channel for detachably holding said plates together, all 35 being arranged whereby upon releasing said detachable holding means said plates may be swung apart with the channel as a fulcrum and then the inner plate lifted out of said channel to complete separation of the plates 40 substantially as shown and described.

9. In an oven door, an outer plate having right angled flanges on all four sides, the flange along one side having an inturned lip thereby constituting a channel along that 45 side, an inner plate also having a right angled flange on all four sides to fit within the flanges and channel of said outer plate, hinge elements located within the space between said plates, means located adjacent the edge 50 of said plate opposite the channel for detachably holding said plates together, all being arranged whereby upon releasing said detachable holding means said plates may be swung apart with the channel as a fulcrum and then 55 the inner plate lifted out of said channel to complete separation of the plates, said inner plate along that side which cooperates with the channel being inwardly offset to receive said lip whereby said lip will lie flush with 60 the exposed face of said inner plate.

In testimony that I claim the foregoing as my own, I have hereto affixed my signature.

WALTER MOLL.
